UNITED STATES PATENT OFFICE.

HERSCHEL G. SMITH, OF SWARTHMORE, PENNSYLVANIA, ASSIGNOR TO THE ATLANTIC REFINING COMPANY, OF PHILADELPHIA, PENNSYLVANIA, A CORPORATION OF PENNSYLVANIA.

APPARATUS FOR FRACTIONATION.

Application filed December 18, 1920. Serial No. 431,552.

To all whom it may concern:

Be it known that I, HERSCHEL G. SMITH, a citizen of the United States, residing in Swarthmore, county of Delaware, and State 5 of Pennsylvania, have invented new and useful Improvements in Apparatus for Fractionation, of which the following is a specification.

My invention relates to apparatus for 10 fractional distillation of mineral oils or hydrocarbons, whereby high selectivity as between different fractions or cuts is obtainable, and thereby securing an increase of yield of a fraction or cut of desired characteristics.

In accordance with my invention, the oil containing the desired cut or fraction is subjected to distillation, yielding a mixture 15 of vapors of oils of various boiling points, the vapor mixture being passed upwardly in heat transfer relation with downwardly flowing condensate containing largely condensed vapors of higher boiling point oils, in subdivided form or well distributed condition, the extent or duration of the heat transfer relation being such as to yield sharply defined or selected cuts or fractions, the degree of sharpness or selection of a cut or fraction being controlled by maintaining 20 suitable difference between the temperature of the vapor mixture from the still and the vapor constituting the selected fraction or cut, such difference in temperature being procured or controlled by suitably controlling diminution of the total heat content 25 in the vapor mixture.

In accordance with my invention, the vapor mixture is cooled by bringing into contact therewith condensate or liquid resulting 30 from the condensation of vapors of the desired fraction or cut, or a distillate, liquid or condensate of similar characteristics, and by controlling the quantity or temperature, or both, of the cooling condensate, the degree of sharpness of the desired cut is controllable.

My apparatus finds application in the refining of petroleum, and particularly in producing therefrom any sharply defined 45 cut or fraction, as for example, sharply defined fractions of naphtha and kerosene or burning oil, the former utilizable for motor

fuel and for mixture with lighter naphthas for motor gasoline. My apparatus also finds application in increasing the yield of gasoline or other fraction of crude petroleum, having a given dry point or boiling point.

For an understanding of my invention and an illustration of some of the various forms my apparatus may take, reference is 50 to be had to the accompanying drawing, in which:

Fig. 1 is a view, partly in section, of apparatus embodying my invention.

Figs. 2 and 3 are vertical sectional views 55 of modified forms of apparatus which may be employed.

Fig. 4 is a plan view, on large scale, of a type of packing employed.

Referring to Fig. 1, S represents a still 70 whose contents may be raised to suitable temperature by fire or other source of heat external thereto, or by steam discharged from the perforated pipe a, to which steam is conducted through the pipe b. Or the 75 heating of the still contents may be accomplished by both external firing and application of steam within the still.

The vapors of the still are conducted through the vapor pipe or line V, in which 80 may be inserted a thermometer c, to the chamber d in the bottom of the tower structure comprising the shell e, of sheet metal or other suitable material, having adjacent its upper end the manhole f and closed at 85 the upper end at g. Communicating with the bottom of the chamber d is the run-back pipe or line D extending into the interior of the still. The tower is preferably covered with heat insulation indicated at h.

Above the chamber d is the grill work or grating i, above which and filling the interior of the tower to suitable height, is the packing j, of any suitable character. This packing constitutes numerous pieces of material, as vitrified earthenware, forming a 95 multitude of interstices and passages.

As an example of various kinds and types of packing that may be employed may be mentioned vitrified tower packing such as 100 used in manufacture or treatment of acid, such as sulphuric acid. Such packing may take any suitable form an example of which is indicated in Fig. 4, in which the external

surface is corrugated, as indicated at *k*, the piece being hollow and having the transversely extending ribs *m*, *m*.

At suitable vertical intervals there are disposed within the tower the deflectors *n* comprising sheet metal members making liquid-tight joints throughout their circumferences with the interior of the tower *e* and having the downwardly and inwardly extending conical surfaces *o*, leaving openings of relatively large diameter, these deflectors serving to prevent downward flow of liquid in contact with the inner walls of the tower *e*, the liquid being deflected from said walls into the packing *j*.

Communicating with the space or chamber *p* at the upper end of the tower is the vapor line or pipe *V*¹, in which may be inserted a thermometer *c*¹, delivering vapors from the tower to the condenser worm or coil *C* disposed within a tank or receptacle *q* into which cooling medium, as water, is introduced through the pipe *r* and carried off by the pipe *s*. The condenser worm delivers through the pipe *t* into the receiving tank or condensate receptacle *R* from which the distillate may be drawn off through the pipe *u*.

Through the pipe *v* controlled by valve *w*, condensate or distillate may be drawn from the tank *R* by the pump *x* and delivered through the meter *y* to the pipe *z*, which extends into the tower and delivers the distillate to any suitable liquid subdividing means or sprayer, an example of which is indicated at *a*¹, consisting of a tray receiving the distillate from pipe *z* and having notches and openings for allowing escape of the distillate, by gravity, in small streams.

The operation is as follows:

Assuming it be desired to procure sharply defined cuts or fractions of naphtha and kerosene, there may be charged into the still *S* petroleum distillate containing naphtha and kerosene. The still is heated or fired at such rate as to raise the charge to suitable temperature, which temperature may be increased at such rate as to effect the desired rate of production of distillate or desired fraction. The mixture of evolved vapors flows through the pipe *V* into the chamber *d* and thence upwardly through the interstices between and passages of the packing *j*, the vapors of oils of higher boiling points first condensing, and those of progressively lower boiling points condensing at greater heights within the tower *e*, with the result that there is an up-flowing stream of vapors and a downwardly flowing stream of condensed oils of boiling points higher than that of the desired fraction or final condensate or product of sharply defined fractionation, these heavier oils flowing back into the chamber *d* and thence through the runback *D* into the still *S*.

By this upward flow of vapors and counter or downward flow of condensed vapors, dephlegmation takes place, in that heat exchange occurs between the rising vapors and descending oil, with the result that the vapors reaching the upper end of the tower are those of oils having more closely the same boiling points than the oils of the vapors delivered by the still through the vapor line *V*; and the boiling points of the oils whose vapors so reach the upper end of the tower *e* are lower than the boiling points of all the oils which are condensed within the tower and flow downwardly through the packing *j*.

At the beginning of the distillation the temperatures of the vapors in the pipes *V* and *V*¹ may not widely differ; in fact, they may be but slightly different, and the vapors delivered into the pipe *V*¹ are those of naphtha, which are condensed in the coil *C* and delivered to the receiver *R*. As the distillation continues, the difference in temperatures registered by the thermometers *c* and *c*¹ will be increased, particularly when there is pumped back through the pipe *z* to the spraying device *a*¹ some of the distillate from the receiver *R*, such distillate constituting the desired fraction or cut, i. e., the final product or final condensate. At the beginning of application of the distillate to the spraying device, the rate of delivery of the distillate may be small, and progressively increased as the distillation proceeds. As the amount of distillate returned to the tower is increased, the difference between the temperatures registered by the thermometers *c* and *c*¹ will increase, and at the end of the distillation period for procuring the naphtha fraction or cut this temperature difference may amount to about 80 degrees F.

The returned distillate effects an accentuated cooling or chilling, in that the distillate in descending through the packing abstracts heat from the rising vapors, causing condensation therefrom of oils whose boiling points are higher than that of the desired distillate or cut, the returned distillate by the consequent absorption of heat being vaporized, but the resultant vapors are those of the desired cut; and they again pass off through the pipe *V*¹ to the condenser *C* and return to the receiver *R* as distillate along with additional distillate representing part of the vapors affected within the tower *e* by the distillate returning thereto.

The rate of return of distillate to the tower is controlled, as by the valve *w*, and by so controlling the rate of supply of distillate to the tower, the distillation and sharp fractionation are controlled.

After the aforesaid naphtha cut has been taken, a similarly sharply defined cut of kerosene or burning oil of desired char-

acteristics may be taken in similar way. After taking the kerosene cut, there will be left in the still a residuum which is principally gas oil which may be utilized for 5 other purposes.

The naphtha obtained in accordance with the above described method may be employed as motor fuel, or may be mixed or blended with lighter naphthas, as casing head 10 naphtha or gasolene, for producing motor gasolene.

In practicing the method as above described, the cost of fractionation, as measured in terms of heat units required or employed, 15 is relatively low, the only heat losses being those occasioned by radiation from the apparatus, as the tower, and the heat delivered to its cooling medium by the condenser C. The heat loss in the condenser may be greatly 20 reduced by using as the cooling medium delivered through the pipe r the oil to be charged into the still S when such still is used in a continuous distillation process, as for example, when the still S is one of a 25 series of two or more interconnected by pipes through which there is delivered from one still, engaged in producing cuts of lower boiling point, oil or residuum to another still of the series engaged in producing a 30 fraction of higher boiling point.

In Fig. 2 the arrangement is similar to that described in connection with Fig. 1. However, the lower end only of the tower e is covered by heat insulation h, and for the 35 remainder of its height it is enclosed in a stack or shell A, spaced from the tower e, air being admitted to the space between the tower and shell through the inlet openings b¹. Above the tower the stack is provided 40 with a damper d¹ whose position is controllable at will by the member e¹. The upper end of the stack may be provided 45 with a removable cover f¹.

The mode of operation is similar to that 45 described in connection with Fig. 1, though in this instance heat is abstracted from the tower into the air passing upwardly between the stack and tower e. Control is effected 50 as described in connection with Fig. 1, by return of distillate through the pipe z into the tower, the distillate being returned preferably at least during part of the operation.

In Fig. 3 the tower e is open at its upper 55 end, whereby uncondensed vapors pass upwardly through the tubes g¹ disposed within the shell B into which air is admitted through the air doors h¹, the air circulating 60 around the tubes and passing upwardly through the hole i¹ in the circular header j¹ with which the upper ends of the afore- 65 said tubes g¹ communicate. The vapors of

the desired fraction pass off from the header j¹ through the vapor line V¹ as before. The air after contact with the tubes g¹ passes off through the stack k¹, the air draft 70 being controllable by the damper m¹.

The mode of operation is similar to that described in connection with Fig. 1, the vapors, however, being further differentiated or fractionated by the condensation taking 75 place in the air cooled tubes g¹, distillate being returned as before through the pipe z, at least during some stage of the operation.

By employment of the apparatus of Fig. 1, 75 dephlegmation in addition to that by the higher boiling condensate from the vapor mixture is secured entirely by re-introduction of distillate into the tower. In Fig. 2 the additional dephlegmation is secured 80 partly by the returned distillate and partly by radiation from the sides and upper part of the tower. In Fig. 3 the additional dephlegmation is secured partly by returning distillate, and partly by radiation from 85 an air-cooled structure other than the tower.

While in the foregoing description reference has been made to return to the dephlegmator of distillate constituting the desired fraction or cut, it will be understood 90 that other suitable material or oil may be employed, provided its characteristics are substantially similar to those of the desired distillate.

The above described method and apparatus 95 make easily attainable great flexibility of control of conditions of distillation for a desired sharply defined fraction; and the method and apparatus lend themselves readily to large capacity operations, since 100 the apparatus may be constructed of any suitable or desired capacity.

What I claim is:

Apparatus for producing a sharply defined fraction of petroleum comprising a 105 still, a dephlegmating tower, deflector members spaced vertically from each other in said tower and having their peripheries in liquid-tight contact with said tower, said deflector members extending downwardly 110 and inwardly to openings, packing material in said tower vertically continuous through said openings, a condenser, a vapor line extending from said tower above said packing to said condenser, and means for returning 115 from the outlet of said condenser to said tower above said packing condensate discharged by said condenser.

In testimony whereof I have hereunto affixed my signature this 16 day of December, 1920.

HERSCHEL G. SMITH.
